UNITED STATES PATENT OFFICE.

RAYMOND J. GREENE, OF SEBRING, OHIO, ASSIGNOR TO THE GEM CLAY FORMING COMPANY, OF SEBRING, OHIO, A CORPORATION OF OHIO.

ORNAMENTED SURFACE AND METHOD OF FORMING THE SAME.

Application filed March 29, 1927. Serial No. 179,292.

This invention relates to ornamenting surfaces of clay and the like, and more particularly to a novel method of ornamenting the surfaces of back walls and other parts of radiant gas heaters.

The object of the improvement is to provide an ornamental surface for clay and the like in which any desired design or effect may be carried out, the finished surface having irregular ribs and valleys, giving a rustic appearance to the article thus ornamented.

An embodiment of the invention is illustrated in the accompanying drawing, in which

Figure 1 is a front elevation of a back wall for a radiant gas heater showing the surface thereof ornamented by the improved method;

Fig. 2, a section taken substantially on the line 2—2, Fig. 1, before the high spots in the surface have been rolled down, and

Fig. 3, a similar section of the finished surface.

Similar numerals refer to similar parts throughout the drawing.

In carrying out the invention to ornament the surface of a back wall for a radiant heater as shown generally at 1, the back wall is first molded of a suitable mixture of fire clay to the general outline required.

A mixture of fire clay and the like of about the consistency of paste is then applied to the surface of the back wall with any suitable tool and worked into any desired design or configuration with proper tools or with the fingers.

This composition is indicated at 2 and in cross section may assume a configuration similar to that shown in Fig. 2, having alternate irregular valleys 3 and ribs 4.

Before this composition has hardened, a roller or the like is passed over the surface, flattening the tops of the ribs 4 as indicated at 5 in Fig. 3 and rolling them out so that the edges project over the valleys 3 as indicated at 6 in said figure, giving an undercut appearance to the surface which cannot be obtained in any other manner.

When the surface has hardened sufficient-

ly, it may be painted in any desired manner. If desired, the back wall may be first baked or burned in a kiln before the paint is applied, or the paint may be applied and the back wall afterwards burned, depending upon the nature of the paint used.

Very artistic results may be obtained by painting the entire surface with one color and after the same has dried, a coat of a different color, preferably darker, is applied to the entire surface, and while wet the flat surfaces 5 are wiped off, leaving the lighter color thereon, while the valleys remain darker or vice versa as desired.

While only one design of ornamentation is illustrated, it will be understood that by the use of different finishing instruments or tools a great number of artistic finishes may be easily formed upon the surface.

Although this finish is described and illustrated as applied to the back walls for radiant heaters, it will be understood that the same is applicable to the radiants themselves, and is adaptable for ornamenting any surface wherein it is desired to obtain a finish of the general character described in which an undercut appearance is desirable.

I claim:

1. The ornamenting process which consists in applying a plastic coating to a surface to be ornamented, forming ribs and valleys in said coating and rolling down the high points of said ribs so that the edges thereof project over the valleys to produce an undercut effect.

2. The ornamenting process which consists in applying a plastic coating to a surface to be ornamented, forming ribs and valleys in said coating, rolling down the high points of said ribs so that the edges thereof project over the valleys to produce an undercut effect, painting the coated surface and permitting the paint to dry, painting the surface with a different color of paint, and wiping the second coat of paint from said flat surfaces while the paint is wet.

In testimony that I claim the above, I have hereunto subscribed my name.

RAYMOND J. GREENE.
